WATER TOY

Robert K. Ostrander, Rolling Meadows, Ill., assignor to
The Quaker Oats Company, Chicago, Ill.

Filed Mar. 3, 1971, Ser. No. 120,790

Term of patent 14 years

The term of this patent subsequent to Sept. 13, 1989, has been disclaimed

Int. Cl. D21—01
U.S. Cl. D34—15 AD

FIG. 1

FIG. 2

FIG. 3

FIG. 5

FIG. 1 is a front perspective view of a water toy showing my new design;

FIG. 2 is a top plan view thereof with the toy figures removed for purposes of clarity;

FIG. 3 is a front elevation thereof with the toy figures removed for clarity;

FIG. 4 is a bottom plan view thereof; and

FIG. 5 is a rear perspective view of the water toy with the toy figures in place as in FIG. 1.

I claim:

The ornamental design for a water toy, substantially as shown.
